UNITED STATES PATENT OFFICE.

ELLA L. COLE, OF NEW YORK, N. Y.

DESIGN FOR A GRIP FOR SKIRTS, &c.

SPECIFICATION forming part of Design No. 25,993, dated September 8, 1896.

Application filed June 25, 1896. Serial No. 596,947. Term of patent 7 years.

To all whom it may concern:

Be it known that I, ELLA L. COLE, a citizen of the United States, residing at New York city, in the county and State of New York, 5 have invented and produced a new and original Design for a Skirt and Trouser Grip, of which the following is a specification, reference being had to the accompanying drawing, forming a part thereof, which represents 10 a clip or grip embodying the features of my design.

The invention relates to a new and original design for grips or clips for holding trousers or holding skirts in place and for holding a 15 belt in close engagement with the trousers or skirt.

The leading feature of the design consists of twin shanks placed one at the rear of the other, the rear shank terminating in spurs.

A is the outer shank, and B the inner shank, 20 the inner shank being returned from the outer shank at the top, and C represents twin spurs, which extend from the lower or free end of the innermost shank.

I claim—
25 The design for a skirt or trouser grip, substantially as shown and described.

ELLA L. COLE.
